UNITED STATES PATENT OFFICE

FREDERICK E. MUNSCHAUER, OF BUFFALO, NEW YORK, ASSIGNOR TO NIAGARA MACHINE AND TOOL WORKS, OF BUFFALO, NEW YORK, A CORPORATION OF NEW YORK

FOLDING MACHINE

Application filed July 3, 1928. Serial No. 290,242.

This invention relates to a folding machine for folding sheets of metal and more particularly to machines of this character in which a bar is employed for turning or bending an edge of a sheet around a leaf during the folding operation, which machines are generally known as bar folders.

In machines of this type, as heretofore constructed, the means for gripping the edge of the sheet preparatory to folding or bending the same necessitated adjustment for adapting the same to the particular thickness of sheet metal which was to be bent or folded.

The object of this invention is to provide a clamping mechanism for folding machines which is capable of being adjusted manually to suit a particular thickness of sheet metal but which is capable of yielding and automatically adapting itself to sheets of metal of greater thickness and thereby avoiding the necessity of readjusting the clamping mechanism for this purpose, whereby the folding of sheets of various thicknesses is facilitated and the output of the machine is increased and the cost of the work reduced accordingly.

In the accompanying drawings:

Figure 1 is a front elevation, partly in section, of the folding machine containing my improvement and showing the parts of the same in an open position.

Figure 2 is a fragmentary vertical transverse section taken on line 2-2, Fig. 1.

Figure 3 is a view similar to Fig. 2 showing the parts in the position which they occupy when the sheet of metal has been partly bent.

In the following description, similar characters of reference indicate like parts in the several figures of the drawings.

The main frame of this machine comprises a longitudinal elevated body 10 and two feet 11 depending from the opposite ends of this body and adapted to rest on a table, bench or other support.

Upon the upper part of the frame body is mounted a folding leaf or blade 12 which projects forwardly therefrom and below this blade is arranged a gage 13. The sheet of metal to be folded or bent is placed with its rear part 14 underneath the front part of the folding blade and with its rear edge against

the gage, as shown in Fig. 2. Then this rear edge portion of the sheet is first raised and clamped against the underside of the blade 12, and thereafter the front part 15 of the sheet is bent rearwardly over the blade so that the rear and front parts are folded at an angle relatively to one another, as shown in Fig. 3.

The clamping of the rear part of the sheet of metal against the folding blade or leaf is effected by means which include a vertically movable clamping jaw 16 which is arranged lengthwise below the folding leaf or blade and provided at its opposite ends with two rearwardly projecting arms 17 which are pivoted by means of horizontal longitudinal pins 18 to opposite ends of the frame body.

Bending of the sheet around the folding blade is effected by means which include a longitudinal folding bar 19 which is pivoted at its opposite ends by pins or trunnions 20 turning in bearings 21 on opposite ends on the clamping jaw, and a folding wing 22 pivoted at its opposite ends on the ends of the folding bar by pins 23, so as to be capable of turning thereon in a vertical plane.

In the open position of the machine the folding bar and wing are swung forwardly and downwardly so that the face of the wing is in front of and flush with the face of the clamping bar 16, whereby the sheet to be folded can be placed on the faces of the folding wing and clamping bar and the rear part thereof projected under the blade and into engagement with the gage, as shown in Fig. 2.

The folding bar and wing are adapted to be swung upwardly and rearwardly for bending the front part of the sheet relative to the rear part thereof so that the sheet is folded, as shown in Fig. 3. The folding bar is manipulated during this time by one or more handles or levers 80 secured to the free edge of this bar. The folding wing turns bodily with the folding bar but is free to swing thereon and adapt itself to the sheet of metal which is being bent. While the folding wing is in its inoperative position the same is supported in a position in which its face is in line with the face of the clamping bar this being preferably accomplished by a stop pin 24 projecting

forwardly from the clamping bar and forming a rest for the folding wing, as shown in Fig. 2.

While the folding bar and wing are in their lower inoperative position the clamping bar is lowered away from the folding blade so as to permit the sheet to be freely inserted therebetween and against the gage. During the initial part of the upward and rearward movement of the folding bar and wing the clamping bar is raised so as to press the rear end of the sheet of metal against the folding blade and hold the latter against displacement while the bending of the sheet is effected during the last part of the upward and rearward movement of the folding bar and wing.

The raising of the clamping bar for this purpose is effected by two rotary cams 25 arranged on opposite ends of the folding bar, 20 concentric with the axis thereof and engaging with two abutments 26 which are relatively stationary and preferably have the form of rollers. Each of these abutment rollers is pivotally mounted on a vertically movable 25 support which is yieldingly mounted on the adjacent part of the main frame, in this case on the adjacent foot or leg of the same.

Although these abutment supports may vary the same consist preferably of rocking 30 supporting arms 27 one of which is arranged over each frame leg or foot 11 and carries the respective abutment roller on its upper side between the ends thereof and is pivoted so as to be capable of swinging vertically by engaging a downwardly opening socket 28 on the rear end of the supporting arm with the upper spherical end 29 of a post 30 rising from the adjacent part of the respective frame leg, as shown in Figs. 2 and 3.

40 In the construction shown in Figs. 1, 2 and 3, each of the supporting arms 27 is provided on the upper side of its front end with a pocket or casing 9 on the bottom of which rests a screw nut 8 having an upwardly projecting tubular neck 7. The upper end of the pocket 9 has an internal screw thread which is engaged by an externally threaded follower 6 which may be turned by a spanner wrench or by any other suitable tool.

50 The screw nut 8 may be held against turning by a pin 5 connecting the same with the bottom of pocket or other approved means, so that this pocket and screw nut are prevented from turning relatively to one another but the same are capable of moving vertically one relatively to the other.

Within the pocket is arranged a spring 4 which surrounds the neck 7 and bears at its lower and upper ends against the screw nut 8 and the follower 6, so that upon tightening or loosening the follower 6 the tension of the spring 4 can be increased or decreased.

Extending through the neck 7 and engaging 65 with the internal thread of the screw nut 8 is an upright supporting screw 3 the lower

end of which bears against the adjacent foot 11 of the frame while its upper end has a flat sided head 2 which permits of turning the same by a wrench. After adjustment of this screw the same may be held against turning by a jamb nut 1 working on the upper part of this screw and engaging with the upper end of the tubular neck 7.

For the purpose of adapting this machine for folding sheet metal of a specified thickness the supporting screws 3 are set so as to permit of freely introducing the rear edge of the sheet to be inserted into the gap between the clamping bar 16 and the folding blade 12. Upon now turning this folding bar and wing upwardly and rearwardly the first effect is that the cams 25 disengage the low parts of their faces from the abutment rollers 26 and engage their high faces therewith, thereby raising the clamping bar 16 and causing the same to grip the rear edge of the sheet metal against the underside of the folding blade. If the throw of this cam is just enough to take up the slack between the sheet of metal and the clamping bar and folding blade, the abutment rollers will be merely turned on their axes but will not be shifted bodily. If, however, the width of the slack space or gap between the sheet metal and the folding blade and clamping bar is less than the throw or rise of the cams, then the abutment rollers are depressed by the high parts of the cams after the slack between the sheet metal and the clamping bar and folding blade has been taken up. As a result, the supporting arms 27 will be depressed and the springs 4 which resist such movement will be compressed. When the cams return to their initial or normal position and present their low faces to the abutment rollers, the latter will be raised by the resilience of the springs.

The springs therefore provide a cushion support for the abutments 26 which permits of effectively clamping the sheet metal and holding the same against displacement during the subsequent bending operation and automatically adapts the clamping action to suit sheets of metal of varying thicknesses without requiring the clamping mechanism to be accurately set for each particular thickness of sheet metal.

By avoiding the necessity of such extra adjustment for each thickness of material which is being bent, the machine can be operated more rapidly and a greater yield can be obtained, thereby enabling this work to be done expeditiously and economically.

The tension of each of the springs 4 can be increased or decreased to suit different requirements by turning either the follower 6 or the supporting screw 3, or by dividing this adjusting function between these two members.

I claim as my invention:

1. A folding machine including a folding

blade; a folding bar adapted to bend material around said blade; a clamping jaw which is adapted to move toward and from said blade and which is pivotally connected with said folding bar; a rotary cam turning with said folding bar; an abutment engaged by said cam; an arm supporting said abutment and pivoted at one of its ends and provided at its opposite end with a pocket; a lower screw nut capable of vertical movement in said pocket but held against turning; an adjusting screw working in said nut and resting on a fixed part; a follower adjustably mounted in the upper part of said pocket; and a spring interposed between said nut and follower.

2. A folding machine including a folding blade, a folding bar adapted to bend material around said blade; a clamping jaw which is adapted to move toward and from said blade and which is pivotally connected with said folding bar; a rotary cam turning with said folding bar; an abutment engaged by said cam; a supporting arm carrying said abutment and provided with a pocket having a bottom; a screw nut arranged in the lower part of said pocket and having an upwardly projecting tubular neck; an adjusting screw engaging said nut and resting on a fixed part; a follower having a screw connection with the upper end of said pocket; and a spring surrounding said screw within the pocket and bearing at its ends against said nut and follower.

3. A folding machine including a folding blade, a folding bar adapted to bend material around said blade; a clamping jaw which is adapted to move toward and from said blade and which is pivotally connected with said folding bar; a rotary cam turning with said folding bar; an abutment engaged by said cam; a supporting arm carrying said abutment and provided with a pocket having a bottom; a screw nut arranged in the lower part of said pocket and having an upwardly projecting tubular neck; an adjusting screw engaging said nut and resting on a fixed part; a follower having a screw connection with the upper end of said pocket; a spring surrounding said screw within the pocket and bearing at its ends against said nut and follower, and means for holding said nut against turning but permitting the same to move vertically.

4. A folding machine including a folding blade, a folding bar adapted to bend material around said blade; a clamping jaw which is adapted to move toward and from said blade and which is pivotally connected with said folding bar; a rotary cam turning with said folding bar; an abutment engaged by said cam; a supporting arm carrying said abutment and provided with a pocket having a bottom; a screw nut arranged in the lower part of said pocket and having an upwardly

projecting tubular neck; an adjusting screw engaging said nut and resting on a fixed part; a follower having a screw connection with the upper end of said pocket, a spring surrounding said screw within the pocket and bearing at its ends against said nut and follower, and means for holding said nut against turning but permitting the same to move vertically, consisting of a pin arranged on said nut and engaging with an opening in the bottom of said pocket.

In testimony whereof I hereby affix my signature.

FREDERICK E. MUNSCHAUER.
